PREPARING INVESTMENTS FOR CASTING

Charles A. McFadden, Upper Darby, Pa., assignor
to Selas Corporation of America, Philadelphia,
Pa., a corporation of Pennsylvania

Application September 26, 1946, Serial No. 699,522

1 Claim. (Cl. 22—196)

1

This invention relates to investment molds.

In casting by the investment method patterns or models formed of wax or like materials are embedded in an investment or investment mold formed of material which is inert with respect to the wax. The wax is then removed from the investment which is cured or baked to prepare it for casting.

In order to remove the wax the exterior of the investment usually is heated to convert the wax therein to a liquid which flows by gravity from the interior of the mold. The wax models or patterns often are of intricate design and formed with traps from which melted wax cannot freely flow by gravity. In such cases the investment must be heated sufficiently at the exterior thereof to bring the melted wax above its flash point temperature, and the wax vapors thus formed pass from the interior of the investment through a sprue opening which extends to a surface of the investment.

In removing wax from an investment in this manner, difficulty is often encountered to remove completely all of the wax from the interior of the investment. This is especially true when removing certain waxes from investments formed of material like cristobalite, for example.

It is an object of the invention to provide an improvement for effectively removing all of the wax from an investment, particularly where difficulty is ordinarily encountered because the wax tends to impregnate into the investment material.

The invention, together with the above and other objects and advantages thereof, will be better understood from the following description taken in conjunction with the accompanying drawing forming a part of this specification, and of which the single figure illustrates one form of apparatus, partly broken away and in section, for practicing the invention.

In the drawing is more or less diagrammatically shown one form that an investment may take. Such investment 10 is provided with a flask 11 in the form of a metal ring. Within the body of material forming the investment 10 a wax pattern or model 12 is embedded in a cavity having a sprue opening 14 which extends to a surface of the investment.

The present invention for completely removing all of the wax from the investment 10 is shown in connection with apparatus including an oven or furnace 15 of a direct gas fired type having side walls 16, roof 17 and floor 18 formed of a refractory material. A suitable door 19 is provided for the oven in one of the side walls 16

2

to gain access into the heating space 20 therein for inserting and removing investments 10 into and from the heating space.

A number of burners 21 are mounted in and form a part of the roof 17. The burners 21 are incorporated in the roof 17 in any desired manner, the number and disposition of the burners being such that the desired heating of the investment 10 in the heating space 20 is effected.

10 The burners 21 preferably are of a direct fired type capable of producing high heating temperatures in the heating space 20. Although not to be limited thereto, burners which have been found especially suitable are of the kind described and illustrated in Hess Patent No. 2,215,079, granted on September 17, 1940, and, if desired, reference may be had thereto for a detailed description of the burner structure.

15 The heating effects produced and developed in the heating space 20 include both radiant and convection heating components. The heat radiated from the burners 21, augmented by the convection heating derived from the heated products of combustion directed toward the investment 10 and downwardly in the heating space 20 provide heating effects for heating the investment 10 rapidly to an elevated temperature.

20 A number of vertically extending conduits 22 are incorporated in the side walls 16 for withdrawing products of combustion from the heating space 20. The lower ends of the conduits 22 terminate at the inner surfaces of the side walls 16 adjacent the floor 18, and the upper ends thereof extend upwardly and terminate a short distance from the roof 17 of the oven 15. At the upper ends of the conduits 22 are provided draft hoods 23 connected to a conduit 24 in which is provided a blower or exhaust fan 25.

25 By providing the draft hoods 23 the full effect of the exhaust fan 25 will not be reflected back to the conduits 22 and cause too rapid withdrawal of the products of combustion from the heating space 20. The draft hoods 23 permit atmospheric air to mix with the products of combustion to dilute and cool the exhausted gases, whereby provision need not be made for the conduit 24 and exhaust fan 25 to handle gases at an unduly high temperature.

30 A shell 26 is fixed to the bottom of the floor 18 in any suitable manner. The floor 18 is provided with an opening 27 which is enlarged at its upper end to provide a cavity adapted to receive a sleeve member 28 upon which the investment 10 is adapted to rest. In the shell 26 is provided a tray 29 which is positioned beneath the opening 27

for collecting melted wax flowing from the interior of the investment 10, as will be explained presently. The shell 26 is provided with a suitable closure member 30 to gain access therein.

When the investment 10 is being heated, hot wax vapors pass from the interior thereof into the shell 26. In order to dilute such hot wax vapors with atmospheric air and also bring down the temperature of such vapors immediately upon passing into the shell 26, a side wall of the shell is provided with one or more elongated slots or openings 31 to permit air from the surroundings to pass into the interior of the shell. An exhaust flue 32 is connected at its lower end to the shell 26, and the upper end thereof is connected to the conduit 24 so that the blower or exhaust fan 25 will also be effective to withdraw the mixture of wax vapors and air from the shell 26.

When the oven 10 is being operated the heating space 20 is desirably maintained at an elevated temperature which may be in the neighborhood of 1200° to 1400° F., for example. The investment 10 rests snugly on the sleeve member 28 which in turn fits tightly in the enlarged cavity of the opening 27, so that gas tight seals are obtained between these parts. The investment 10 is heated to a desired high temperature by the heating effects produced and developed in the heating space 20, whereby the wax model 12 is melted and the wax flows by gravity from the investment 10 through the opening 27 into the tray 29 in the shell 26.

The products of combustion are withdrawn from the bottom part of the heating space 20 through the vertical conduits 22, and such spent gases mix with air drawn into the draft hoods 23 by the exhaust fan 25. The mixture of air and the products of combustion may be discharged by the fan 25 to the exterior of the enclosure in which the oven 10 is installed.

In many cases the wax models are of intricate design and formed with traps from which melted wax cannot freely flow by gravity, as indicated at 13 in the drawing. Any melted wax which is trapped in the investment mold 10 is heated above its flash point temperature, and the wax vapors thus formed pass from the investment 10 through the opening 27 into the shell 26. The wax vapors passing into the shell 26 are diluted by relatively cool atmospheric air drawn into the shell through the opening or openings 31 by the action of the exhaust fan 25. The mixture of wax vapors and air is withdrawn from the shell 26 through the vertical flue 32 and mixes with the gases in conduit 24 which, as previously explained, are discharged from the exhaust fan 25.

The apparatus just described possesses certain advantages in that curing and baking of the investment material is accomplished simultaneously with the removal of wax from the investment 10. In addition, the melted wax and wax vapors pass from the interior of the investment 10 in a path of flow out of physical contact with the heating space 20. When the heating of the investment 10 is completed, the refractory investment material is properly conditioned and a cavity is formed therein which is identical in configuration to the wax model 12 removed therefrom as a result of the heating just described.

In removing wax from an investment mold in the manner just described, difficulty is often encountered to remove completely all of the wax from the interior of the investment. I have discovered that complete removal of wax from the interior of an investment can be accomplished

by blocking the sprue opening 14 to increase the temperature to which the interior of the investment is heated. The sprue opening 14 desirably is not blocked when the investment 10 is initially heated but only after a major portion of the wax flows in a liquid state from the interior of the investment.

In order to block the sprue opening 14 in accordance with the present invention, a gate 33 is provided which is pivotally connected at 34 to the bottom of the floor 18. When the investment 10 is initially heated, the gate 33 remains in its solid line position and hangs vertically downward from its pivotal connection 34. After a major portion and preferably substantially all of the melted wax, other than the melted wax in the traps 13, flows by gravity from the investment 10 into the tray 29, the gate 33 is moved to its horizontal position and locked in such horizontal position by a rotatable latch member 35, as indicated in dotted lines in the drawing. The gate 33 is moved from its open to its closed position by removing the closure member 30 to gain access into the shell 26.

Although I do not wish to be limited thereto, it is my belief that certain waxes upon heating tend to impregnate into the investment material. With continued heating the wax impregnating the investment material then carbonizes. By blocking the sprue opening 14 after a substantial portion of the wax is removed from the investment 10 in a liquid state, heat losses from the interior of the investment are reduced and the temperature to which the interior of the investment is heated is increased, thereby facilitating the removal of the remaining wax from the investment.

The blocking of the sprue opening 14 by the gate 33 is not complete in the sense that a gas tight seal is produced, but rather is of such a nature that gases can pass through the blocked opening in the gap between the gate 33 and the bottom of the floor 18. In this way wax vapors expelled from the interior of the investment 10 can be displaced by air in the shell 26 to promote oxidation of the carbonized wax material and insure complete removal of the wax from the interior of the investment with a minimum amount of heating and in the shortest possible length of time.

While the material forming the pattern is referred to as a "wax" in the foregoing description, it is to be understood that this term in both the description and claim is intended to cover not only waxes but also resins, plastics and like materials which are suitable for use in preparing investments of refractory material for casting.

Although I have shown and described a particular embodiment of my invention, it will be apparent to those skilled in the art that modifications and changes may be made without departing from the spirit and scope of the invention as pointed out in the following claim.

What is claimed is:

In the art of removing an expendable pattern from an investment that has a cavity in which the pattern is received and an opening extending from the surface of the investment to the cavity, the improvement which consists in placing the investment in a heating space with said opening over an opening in the bottom of said heating space, applying heat to said space to heat the investment to a temperature sufficient to liquefy the pattern so that it may flow by gravity through the opening in the investment and the opening

in the heating space out of said heating space, and after the liquefied pattern has stopped flowing increasing the temperature of the heating space by blocking the heat losses through the opening in the bottom of said heating space to 5 vaporize any of the pattern remaining in said cavity.
